DESIGN FOR A COMBINED CALENDAR STAND AND HORIZONTAL THERMOM- ETER

Martin E. Trolle, St. Paul, Minn., assignor to
Brown & Bigelow, St. Paul, Minn., a corpora-
tion of Minnesota

Application November 27, 1944, Serial No. 116,562

Term of patent 14 years

(CL. D74—5)

To all whom it may concern:

Be it known that I, Martin E. Trolle, a citizen of the United States, residing at St. Paul, county of Ramsey, and State of Minnesota, have invented a new, original, and ornamental Design for a Combined Calendar Stand and Horizontal Thermometer, of which the following is a specification, reference being had to the accompanying drawing, forming a part thereof:

Figure 1 is a front elevational view of a com-

bined calendar stand and horizontal thermometer, showing my new design.

Figure 2 is a side elevational view of the same.

The dominant features of my design reside in the parts shown in full lines.

I claim:

The ornamental design for a combined calendar stand and horizontal thermometer, as shown and described.

MARTIN E. TROLLEN.
